UNITED STATES PATENT OFFICE.

FRANK RUDOLPHI, OF NEW YORK, N. Y., AND OLAF OSTLIN AND MAGNUS E. WIDELL, OF MAYWOOD, ILLINOIS, ASSIGNEES TO AMERICAN CAN COMPANY, OF NEW YORK, N. Y., A CORPORATION OF NEW JERSEY.

CAN-BODY-SIDE-SEAM-SOLDERING MACHINE.

1,178,946.

Specification of Letters Patent. Patented Apr. 11, 1916.

Application filed July 3, 1911. Serial No. 636,659.

To all whom it may concern:

Be it known that we, FRANK RUDOLPHI, a citizen of the United States, residing in New York, in the county of New York and State of New York, and OLAF OSTLIN and MAGNUS E. WIDELL, citizens of the United States, residing at Maywood, in the county of Cook and State of Illinois, have invented a new and useful Improvement in Can-10 Body - Side - Seam - Soldering Machines, of which the following is a specification.

This invention relates to an improvement in can body machines of the general type and character of that illustrated in the patent to Frank Rudolphi, No. 956180, dated April 26, 1910.

The improvement relates more particularly to the means employed for moving the can bodies through the machine, past the soldering devices and the wiper or device for removing the surplus solder. In this machine, after the can body is formed and delivered to the horn by the usual means, each can is gripped by a gripping device 20 carried by an endless chain in such manner as to be held firmly against any possibility of rotation by the action of any soldering devices, or any manipulations incident to soldering, and carried continuously without 25 pause until the seam has been soldered and wiped and the can body is discharged. In the most approved form of can body machines, of which the Rudolphi patented machine above referred to is an example, the 30 can body has been moved along the horn by a reciprocating conveyer which moves the can body a short distance at a time with repeated impulses by engagement with retractile dogs. The advantage of the continuous 35 movement of an endless chain over this intermittent movement of the can bodies is not only a greater simplicity of the actuating parts of the machine, but also the avoidance of uneven adherence of solder to 40 the can, due to the starting and stopping of the same while the melted solder is being applied by the soldering device.

A further advantage is the avoidance of any tendency to deform the cylindric shape

of the can body by the means commonly used to hold the can against rotation on the horn, in the present machine the can being held against rotation by the means which advances it continuously, namely, by the can body grippers carried at intervals by the chain, and gripping each can, continuously until it is discharged from the machine.

A further advantage of the employment of the grippers, which hold the can firmly against any rotation, is that this firm holding enables the placing of a wiping wheel or roll diagonally or at an angle to the axis of the can which operates to wipe the solder more efficiently and thoroughly from the seam than is done by the employment of a wiper rotating in a plane parallel to the can axis.

In the accompanying drawings which form a part of this specification, Figure 1 is a side elevation of the front section of the machine, showing where the can body blank is fed into the machine, where it is formed, double seamed and delivered to the horn; Fig. 2 is a continuation of the side elevation shown in Fig. 1, and illustrates the soldering bath, the wiper and a part of the cooling device and the means for conveying the can continuously past these stations; Fig. 3 is a further continuation, showing the final end of the machine, the means of discharging a can from the continuous carrier and the supplementary can conveyer for carrying the cans to a bin or place of delivery; Fig. 4 is a vertical cross section on the line 4—4 of Fig. 1, showing the horn in section, the means for driving a solder bath roll and the beginning of the chain conveyer; Fig. 5 is a vertical section on the line 5—5 of Fig. 2, showing the horn, the solder roll, the solder bath, the means for heating the solder bath and showing the conveyer chain in section; Fig. 6 is a vertical section on the line 6—6 of Fig. 2, showing the revolving horn supporting roll and the gearing for driving said roll, and also for driving the wiper. Fig. 7 is a vertical section, taken on line 7—7 of Fig. 3, showing the final revolving roller for support-

ing the horn and the gearing for driving the continuously moving carrier chain; Fig. 8 is a partial plan view of the driving mechanism, shown in Fig. 7; Fig. 9 is a partial section on the line 9—9 of Fig. 7; Fig. 10 is a plan view of the reciprocating can blank feed for carrying the blank to the body former horn and for carrying the formed can body from said former horn and delivering it to the continuous-chain carrier; Fig. 11 is a partial elevation upon a somewhat larger scale of the main or conveying horn; Fig. 12 is a side elevation, upon a still larger scale, of a portion of the carrying chain 15 and showing one of the gripping devices; Fig. 13 is a vertical section on the line 13—13 of Fig. 12; Fig. 14 is a partial plan view, showing the gearing for driving the solder bath roll and the main longitudinal driving shaft; Fig. 15 is a partial plan view, showing the diagonal wiper and its driving gear; Fig. 16 is a vertical cross section on the line 16—16 of Fig. 3.

The can body making machine shown in the above drawings embodies the usual feed device for feeding the can body blanks one by one from a stack of them indicated at 21, an intermittently moving conveyer 22 for moving each blank first to the edge folding or hook forming devices, then to an intermediate station between the hook formers and the usual body former horn, and then to the body former horn, two pairs of clamp devices for clamping the ends of the blank 35 during the edge folding operation, an intermediate clamp for clamping the middle portion of the clamp during the hook forming operation, edge folders, an expandible and collapsible body former horn arranged 40 below the guides for the can body blank, a clamp or device above the horn for clamping the middle portion of the blank against the horn, body formers around the horn for folding the can body blank around the horn 45 and for causing the oppositely turned hooks or edge folds on the blank to lap past each other so that they will interengage as the horn expands to draw the hooks together and size the can body preparatory to the 50 bumping or seam closing operation, a reciprocating bumper or seam closing device for closing the seam, and an intermittently moving conveyer 23 for moving the folded and bumped can body onto the soldering 55 horn 24, connected to the end of the body former horn. Below the soldering horn is the usual fluxing or acidizing device 25 and the usual molten solder bath 26 containing a rotating solder applying roller 27 for applying the solder to the side seams of the 60 can bodies 28; also at a station farther along, there is a rotary wiper 29 for removing the surplus solder from the outside surface of the can body adjacent to the seam. This

wiper 29, for more effective action, is mounted in a plane of rotation standing at a slight angle to the axis of the can body soldering horn 24 and the gearing 30, 31 is adapted to this angular position of the rotary wiper, as will be seen by reference to Fig. 15. The rotary wiper, swung on the shaft of the gear 31 is held yieldingly up against the under surface of the can body by a weight 32. The means for continuously moving the can bodies along the soldering horn, over the 75 soldering bath, past the rotary wiper and to the final discharge, consists of an endless chain 33, provided at regular intervals with grippers 34. At the entering end of the soldering horn this chain rides over the 80 sprocket 35. At the leaving end of the horn, it rides over the sprocket 36. Referring to Figs. 7 and 8, this latter sprocket 36 is carried on the shaft 37, provided with the gear 38, meshing with the gear 39 on the shaft 40, which latter shaft is driven by the bevel gears 41, 42, the sprocket 43, chain 44 and sprocket 45 on the longitudinal main shaft 46. This shaft 46 runs the length of the machine and is driven by the bevel gears 47, 48, (Fig. 1) sprocket 49, and chain 50 from the shaft 51, on which shaft is the band wheel 52 or main or prime source of power in the machine. Turning for convenience to Fig. 11, it will be noted that the 95 sprocket 36 is mounted on a slotted framework 53 secured to the frame of the machine by a bolt 54, so that any slack in the chain may be easily taken up as occasion may require. It will also be noted that attached to the 100 sprocket 36 is the plate carrying the pins 55 (hereinafter described), which is cut away to permit free passage of the grippers, cavities 56 being provided for this purpose. The chain 33 (Fig. 12) is composed of links 105 57, 58 and a special gripper link 59. This gripper link 59 is made with a foot 60 having an inclined front edge 61. Pivoted to this gripper link at 62 is the gripping clamp 63, having the swinging surface or gripping face 64, the guard extension 65 and the actuating projections 66. As will be understood, each set of members 60 and 63 constitutes a pair of jaws adapted to grip the can and the guard extension 65, (which as shown 115 in the drawing is preferably formed integral with the member 63), may be considered as a pivotally mounted dog having its lower end or leg projecting across the path of the can as the latter enter between the jaws, the 120 cans actuating the dog and the latter in turn actuating the member 63 to grip the cans. As will be understood, when a can body 28 is firmly gripped between the foot piece 60 and the curved gripping face 64, the forward pull of the chain will tend at all times 125 when in motion to tighten the grip.

When the grippers are carried over the

sprocket 35, the actuating projections or tail pieces 66 of the grippers strike against the shaft 351 of this sprocket and being thus dragged backward, the mouth of the 5 gripper is opened as is indicated at Fig. 11, where one of the grippers is in the act of passing this shaft. In this position, the gripper is brought against the edge of the can end by the movement of the chain and 10 the can is thus strongly and firmly gripped or embraced between the upper face of the foot 60 and the lower face of the swinging surface 64. This engagement is sufficiently firm and secure so that neither the rotary 15 rubbing of the soldering roll in a direction at right angles to the axis of the can, nor the rubbing of the wiper against the lower periphery of the can, at an angle, will cause the can to turn or become loosened from the 20 hold of said gripper. So held, the cans are conveyed along over the horn by the movement of the chain until the tails of the grippers strike the plate 67 placed in their path on the stationary framework of the 25 machine, at a point near the end of the soldering horn. As each gripper encounters this plate, its jaw is opened thereby and the grip on the can released, the guard extension 65, however, still being kept pressed 30 against the can body to push the same along. The tail of the gripper rides under the said plate 67 for nearly or quite the length of a can body, pushing the can thus partly off the horn, but just before the can body is 35 discharged, the tail of the gripper engages the pin 55 on the sprocket 36 and this insures that the gripper shall not accidentally clamp the can to prevent its discharge from the horn. The cavities 56 permit the 40 grippers to ride around the sprocket in the open condition, and this open condition, if it is not maintained throughout the return of the chain to the starting point, is again insured at the starting point by the tail of 45 the gripper riding upon the shaft 351 of the sprocket 35, as before explained.

When the can passes from the soldering horn, it falls on the extended conveyor 68 (Fig. 7) driven by the gearing 69, 70, 50 sprocket 71, and chain 72, from the shaft 46. The customary air cooling device, consisting of a pipe for blowing air upon the passing soldered can is indicated at 73. The rotary soldering roll 27 (Fig. 4) is driven from the 55 shaft 46 by the gearing 74, 75, 76, one of the sprockets 761, 762 or 763 and chain 77.

Referring to Figs. 11, 12, 13, the soldering horn 24 has at its upper part in the member 241 a groove 242,—to accommodate 60 the gripper foot and the guard extensions 65 of the gripper while holding the can. The actuating projections or tails 66 are made in two parts to straddle the guiding frame piece 78, so that the chain is kept at

all times from lateral vibration, and the 65 cans held firmly by the chain and the gripper from turning.

Upon occasion it is desirable that the means for conveying a can along the soldering horn shall be capable of removal to get 70 at the said horn, and for other reasons. In the present machine, this is accomplished by mounting the double guiding frame 78 which carries the chain 33 and sprockets 35 and 36 on a plurality of bell crank levers 75 82, 83 and 84, each of which has one arm pivoted to the stationary framework of the machine by the pivots 85, 86 and 87 respectively. Each of the other arms of each of the bell crank levers is pivoted to an adjustable connecting bar 89 which at one end is also pivotally connected to an operating lever 88, the latter being pivoted on, and oscillatable about, the stationary pivot 87 whereoy as the lever 88 is swung about the 85 stationary pivot 87 the bell crank levers 82, 83 and 84 will be swung about their respective pivot points 85, 86 and 87, thus raising the frame 78 and the chain and sprockets carried thereby. 90

The rotary wiper 29, set at an angle to the axis of the can to be wiped acts simultaneously both across and in line with the seam and this is more effective in its removal and consequent saving of the solder. 95 The difficulty of driving from the straight shafting of the machine such an angularly placed wiper in such manner as to permit the wiper to be weighted is simply and effectively obviated by pivoting the wiper 100 carriage 79 on the shaft 80 carrying the bevel gear wheel 31, which shaft takes its power by the gearing 91, 92, shaft 93, and gearing 94, 95 from the main longitudinal shaft 46. 105

In machines of this character, it is important to provide means for adjusting or changing the rotative speed of the soldering roller in relation to the lineal travel of the cans over said soldering roller since upon 110 this relation depends the character of the soldering done. This is simply and effectively accomplished in the machine illustrated by providing several sprocket wheels of differing sizes, as 761, 762, 763 on the 115 shaft of the gear 76, from one to another of which differing wheels the chain 77 may be changed as desired, thus increasing or diminishing the speed of rotation of the soldering roller in relation to the speed of 120 rotation of the shaft 46 and consequently in relation to the lineal speed of travel of the cans carried by the chain driven from said same shaft 46. To facilitate this changing of the chain from one size 125 sprocket 761, 762, 763 to another, the sprockets, and their gear 76, are mounted on the arm 764, pivoted on shaft of the inter-

mediate gears 74, 75, and having a slotted arc 765 and locking nut 766 for loosening and tightening the chain 77 by moving the sprockets away from or toward the soldering roll.

Having described the invention, the following claims are made:

1. In a side seam soldering machine having a rotary soldering roller, the combination with means for carrying the cans over the soldering roller and means for rotating said roller, of means for adjustably changing the relation of the speed of rotation of the soldering roller and the speed of lineal movement of the can carrying means, substantially as specified.
2. In a side seam soldering machine having a rotary soldering roller, the combination with means for carrying the cans over the soldering roller and means for rotating said roller, of means for adjustably changing the relation of the speed of rotation of the soldering roller and the speed of lineal movement of the can carrying means, said means for changing the relative speed including a chain and a plurality of driving sprocket wheels of different diameters, substantially as specified.
3. In a side seam soldering machine having a rotary soldering roller, the combination with means for carrying the cans over the soldering roller and means for rotating said roller, of means for adjustably changing the relation of the speed of rotation of the soldering roller and the speed of lineal movement of the can carrying means, said means for changing the relative speed including a chain, a plurality of driving sprocket wheels of different diameters and a swinging adjustable arm upon which said sprocket wheels are mounted, substantially as specified.
4. In a side seam soldering machine having a solder bath over which the cans are adapted to be carried, the combination with a soldering horn along which the cans are conveyed, of an endless chain having grippers for carrying the cans, which grippers are provided with can-actuated means whereby the said grippers are automatically caused to grasp the edge of the can body by the resistance of said body to longitudinal movement, said endless chain being mounted on a movable framework, whereby the chain may be raised away from the soldering horn, substantially as specified.
5. In a side seam soldering machine having a solder bath over which the cans are adapted to be carried, the combination with a soldering horn along which the cans are conveyed, of an endless chain having grippers for carrying the cans, said endless chain being mounted on a movable framework, whereby the chain may be raised away from the soldering horn, and raising

means including a plurality of bell crank levers pivoted to the stationary frame of the machine and to said movable framework, substantially as specified.

6. In a can body side seam soldering machine having a solder bath over which the cans are adapted to be carried, the combination with a solder horn along which the cans are conveyed, of an endless chain having grippers for carrying the cans, said chain being mounted on a movable framework, means for moving said framework away from the solder horn, including a series of bell crank levers pivoted to the stationary frame of the machine and to said movable framework, an operating lever and a connection from each of said bell crank levers to the operating lever, substantially as specified.

7. In a can body soldering machine having a solder bath, the combination with means for moving cans over said bath, of a rotary wiper rotatable in a plane intersecting the axis of the can bodies and their line of motion at an angle less than ninety degrees, substantially as specified.

8. In a can body soldering machine having a solder bath, the combination with means for moving the cans over said bath, said means including a chain provided with grippers, of a wiper rotatable in a plane at an angle to, and intersecting, the axes of the can bodies and their line of bodily movement, substantially as specified.

9. In a soldering machine of the character described, in combination: a solder bath; a solder applying roller; means for moving can bodies over the solder bath; and a gravity controlled rotary wiper rotatable in a plane transverse to the path of travel of the can bodies and adapted to wipe the soldered seam crosswise thereof, substantially as specified.

10. A gripping device comprising a pair of jaws capable of relative movement, one of said jaws having a cam-like gripping face to coöperate with the other jaw, one of said jaws having means to hold it from turning, and one of said jaws having an arm which is engaged by the article being gripped to automatically cause the cam gripping action of the jaws.

11. In a soldering machine of the character described, in combination: means for applying solder to can bodies; a horn; means for moving can bodies along said horn; and a solder wiper device, said device including a pivotally mounted carrier having a rotatably mounted disk thereon and mechanism for positively rotating said disk, the disk being rotatable in a plane at an angle to and intersecting the path of movement of the can bodies, substantially as specified.

12. A traveling carrier having a device thereon for gripping cans or the like, com-

prising a pair of relatively movable jaws, one of said jaws having an arm which extends across the space between the jaws, which arm is engaged by the cam when it is in position to be gripped, to automatically cause the gripping action of the jaws, and the other of said jaws being held from turning by said carrier.

13. In a soldering machine of the character described, in combination: a soldering horn; means for applying solder to can bodies while on said horn; and means for moving can bodies along said horn including an endless conveyer provided with a plurality of can body gripping devices, each gripping device including a pivoted element having a projection adapted to be engaged by the end of a can body before the can body is gripped, substantially as specified.
14. A gripping device comprising a pair of pivotally connected jaws, one of said jaws having an arm which extends across the space between the jaws, which arm is engaged by the can body edge when it is in position to be gripped, to automatically cause the gripping action of the jaws, and the other of said jaws having means to hold it from turning.

15. In a soldering machine of the character described, in combination: a solder bath; a solder applying roller; a horn disposed adjacent said roller; and means for moving can bodies along said horn, said means including an endless conveyer provided with a plurality of spaced can body gripping devices, each of said devices including a pivoted element having a projection thereon adapted to be engaged by the end of the can body to thereby close the gripping device, substantially as specified.

16. In a soldering machine of the character described, in combination: means for applying solder to can bodies; and means for moving can bodies in a path adjacent said solder applying means and including an endless conveyer and a movably mounted framework by which said conveyer is carried, whereby the endless conveyer is movable toward and from the solder applying means; substantially as specified.

17. In a soldering machine of the character described, in combination: a solder bath; a horn along which can bodies are adapted to move; a series of grippers arranged parallel with the horn for holding and moving the can bodies; means for moving the grippers along the horn; and hand operated mechanism connected with the grippers and their moving means, which is operable at will to raise the grippers as a series away from the horn.

18. In a soldering machine of the character described, in combination: a solder horn; a solder bath located adjacent thereto; a solder roll having its axis parallel to the

horn; a conveyer for moving can bodies along said horn; and means for adjustably changing the relative rotatable speed of the solder roll and the lineal speed of the can bodies being moved along said horn; substantially as specified.

19. A conveyer of the character described comprising a longitudinally extending supporting bar, an endless conveyer extending above said supporting bar, a sustaining means for said conveyer including a supporting wheel at one end of said endless conveyer, releasing devices mounted upon said wheel and positioned diametrically opposite each other, can holding devices carried by the endless conveyer, the distance between the holding devices being equal to that between the releasing devices whereby the holding devices will be positioned in alignment with the releasing devices passing around the wheel, the releasing devices disconnecting the cans from the holding devices upon reaching the ends of the supporting bars.

20. A traveling carrier having a device thereon for gripping cans or the like, comprising a pair of pivotally connected jaws one of which is attached to the carrier and the other of which has an arm which extends across the space between the jaws to be engaged by the can body edge, and means for throwing the said arm forward, when the can body is to be released, to eject the same from the jaws.

21. In a machine of the class described, the combination of means for internally supporting can bodies, conveyer means, movable always in the same direction having means for preventing the can bodies from rotating, and a continuously rotating solder roll, said solder roll having an axially elongated surface and rotatable about an axis parallel to the line of travel of the cans as same are moved by the conveying means, said internally supporting means and said continuously movable conveyer means being adapted to convey can bodies adjacent to said solder roll, whereby the side seams of said bodies are filled with molten solder, substantially as specified.

22. In a machine of the class described, the combination of side seam soldering means, including a continuously rotating solder roll immersed in molten solder, a means for wiping surplus solder from a freshly soldered side seam and a means for cooling the soldered side seam, a can body support adapted to support cans in transit successively to said side seam soldering means, said wiping means and said cooling means, a conveyer having means for preventing cans from turning and movable always in the same direction, for conveying cans along said supporting means adjacent to said solder roll, whereby the side seams

are filled with molten solder, adjacent to said wiping means, whereby the surplus solder is wiped from the freshly soldered side seams and adjacent said cooling means whereby the soldered and wiped seam is cooled, substantially as specified.

23. In a side seam soldering machine, the combination of a solder bath over which the cans are adapted to be carried, a horn for supporting and guiding the cans, means for applying solder from the said bath to the seams of the cans, an endless chain, means for mounting and actuating the same parallel with the said horn, and automatically 10 acting grippers each comprising two jaws pivotally connected, one of which jaws is 15

fixed to the chain and the other of which jaws is movable and provided with can-actuated means engageable and operable by the edge of the can body the resistance of which latter causes the automatic closing and gripping action of the said jaws. 20
